Atty.

UNITED STATES PATENT OFFICE.

ADOLPH GRUHN, OF MACON, GEORGIA.

ROLLER-RUBBING WASHER.

Application filed March 17, 1922. Serial No. 544,554.

To all whom it may concern:

Be it known that I, ADOLPH GRUHN, a citizen of the United States, and resident of Georgia, in the city of Macon and county 5 of Bibb, Georgia, have invented certain new and useful Improvements in Roller-Rubbing Washers, of which the following is a specification.

This invention relates to rubbing devices 10 for laundering purposes and the principal object of the invention is to provide a hand rubber which shall be efficient in operation, and is of such simple and economical construction as to permit of the manufacture 15 and sale of the same at a minimum cost.

Another object of the invention is to provide, in a hand rubber of the type comprising a handle member having revoluble rollers associated therewith, a novel form 20 of bracket structure for securing the rollers to the handle.

A still further object of the invention is to provide a hand rubber having a splash 25 guard overlying one of the rollers to prevent splashing of the operator during the rubbing process.

Other objects of the invention, as well as the particular construction, combination and arrangement of parts constituting the invention, will be more readily understood 30 from the following description and accompanying drawings; in which drawings:

Fig. 1 is a top plan view of a hand rubber constructed in accordance with my invention.

Fig. 2 is a rear elevation.

Fig. 3 is a central longitudinal sectional view.

Referring more particularly to the drawings, 5 designates a handle member herein shown as of substantially rectangular form and composed preferably of wood, although it is obvious that metal or other suitable material may be substituted.

40 Two bars designated, respectively, 6 and 7 are secured, as by means of bolts 8, to extend transversely across the underside of the handle member 5, so as to project a considerable distance beyond the lateral margins of the latter, and the ends of these bars 45 are turned downwardly to provide depending bracket arms 9 and 10.

The numeral 11 designates a fluted roller or cylinder revolvably journaled between the depending bracket arms 9 and the numeral 55 12 designates a similar roller or cylinder journaled in like manner between the depending bracket members 10.

A splash guard indicated at 13 is arranged to overlie the rear roller 12, so as 60 to prevent splashing of the operator during the rubbing process. This guard is of substantially the same length as the rollers and is curved transversely. The upper edge of the guard is clamped between the handle member 5 and the bar 7, and is held in place by the bolt 8, securing the bar to the handle member.

In practice, when rubbing clothes with 70 my invention, the handle member 5 is grasped and operated so that the roller 12 constitutes the rear roller with the splash guard overlying the same and effective to prevent splashing of the sleeve or hand of the operator.

This hand rubber is designed to do away 75 with the practice of rubbing the clothes by hand on a corrugated wash board and consequently results in saving the knuckles from abrasions and soreness as well as from other 80 injuries caused by foreign bodies in the clothes.

Having thus fully described my invention, it is to be understood that I do not desire to limit myself to the exact construction, combination and arrangement of parts disclosed herein, as various modifications 85 could be resorted to within the scope of the appended claim.

What I claim as my invention is:

A device of the class described, comprising 90 a handle member, transversely extending bars secured to the underside of the handle member and provided with depending end portions affording bracket arms a roller carried by the arms of each bar a guard supported on one of said bars and secured to the underside of the handle member.

In testimony whereof I hereunto affix my 100 signature.

ADOLPH GRUHN.
